GUY V. NEWTON AND ERNEST BLACKBURN, OF LOS ANGELES, CALIFORNIA; SAID BLACKBURN ASSIGNOR TO SAID NEWTON.

MECHANISM FOR REVOLVING TYPEWRITER CYLINDERS.

Application filed January 12, 1927. Serial No. 180,603.

This invention has to do generally with typewriters, and is more particularly concerned with devices for rotating typewriter cylinders or platens.

5 The cylinders of usual typewriters are rotated either by manipulation of the cylinder knobs or through actuation of a line-spacing lever, such actuation engaging a dog with a ratchet wheel provided on the end of the cylinder. The character of the line spacing mechanism is such that the angular movement of the cylinder during each actuation of the lever is comparatively small, usually only enough to advance the paper on the cylinder 10 one, two or three lines. In feeding the paper initially into the typewriter, it is necessary that the cylinder be revolved by twirling the platen knobs, since to bring the paper into position to receive the type the cylinder must 15 be revolved to a much greater extent than may be accomplished by several actuations of the spacing lever.

Therefore, it is among the objects of our invention to provide a mechanism whereby 20 a single throw of an operating lever will revolve the cylinder sufficiently to bring the paper into position to receive the type. While this is a feature which is of advantage during ordinary letter writing or envelope addressing, it is of special advantage in filling 25 in names and addresses on form letters, where the operator must insert each sheet into the typewriter for the purpose of filling in only a few lines. In spite of the fact that only 30 a few lines are to be typed, the same operation as to insertion and proper lining up of the paper is necessary as though a full letter were to be written, and consequently any device which speeds up the initial step of advancing 35 the paper to a position to receive the type greatly increases the capacity and efficiency 40 of a given machine and its operator. The same is true in addressing envelopes, for by a single stroke of the operator's hand an envelope is drawn from starting position to the position where it is to receive the type.

In connection with the filling in of form letters, the device is particularly efficient in that it is finely adjustable so a single stroke 45 of the operating lever will bring the blank to be filled in to a proper position with respect to the type, and having been set to

have this given stroke, every subsequent letter inserted will be drawn to the same relative position, perfect register thus being had 55 with the form portions of the letters.

The device is of such a nature that when occasion arises to dispense with the rapid feed feature, the cylinder may be rotated in the normal manner, either by the spacing lever 60 or end knobs, without interference from the device. Furthermore, the device is of a relatively simple nature and may be made up in such light form that it does not over-weight 65 the carriage to a degree tending objectionably to resist easy bodily movement thereof.

There are many other features of the invention which may be discussed to better advantage in the following detailed description, reference being had to the accompanying 70 drawings in which:

Fig. 1 is a fragmentary plan view of the carriage portion of a typewriter to which an embodiment of my invention has been applied; the paper table being thrown forward- 75 ly out of operative position;

Fig. 2 is a view of Fig. 1, partly in broken away section and as viewed from the position of arrow 2; the paper table being turned back to operative position;

Fig. 3 is an enlarged fragmentary section on line 3—3 of Fig. 2;

Fig. 4 is an enlarged section on line 4—4 of Fig. 2;

Fig. 5 is an enlarged fragmentary section 85 on line 5—5 of Fig. 2;

Fig. 6 is a view of Fig. 2 as viewed from the left thereof;

Fig. 7 is a section on the irregular line 7—7 of Fig. 6;

Fig. 8 is a fragmentary section on line 8—8 of Fig. 6;

Fig. 9 is a section on the irregular line 9—9 of Fig. 2 but showing the mechanism in another position;

Fig. 10 is a section on line 10—10 of Fig. 7;

Fig. 11 is an enlarged section on line 11—11 of Fig. 2;

Fig. 12 is a section on line 12—12 of Fig. 2, but showing certain of the parts in changed 100 position;

Fig. 13 is an enlarged, fragmentary section on line 13—13 of Fig. 12; and

Fig. 14 is a section on line 14—14 of Fig. 2.

Since the construction of usual typewriter carriages and parts thereof are well known to those skilled in the art, we have represented these more or less conventionally. For instance, we have shown a carriage generally indicated at 10 as including a frame 11 on which is journalled at 12 the usual cylinder shaft sections 13 carrying usual cylinder or platen 14 and turning knobs 15. The connection between carriage frame 11 and the body frame conventionally indicated at 9, is not shown here since it is of no importance to the present invention, and may be of any well known, usual type.

15 Journaled on shaft 13 at one end of the cylinder is a ratchet wheel 16, the shaft section including a spindle 13^a being movable longitudinally through both cylinder and wheel, though being held constantly in driving relation with the cylinder in the usual manner. When the spindle and its knob 15 are in the position of Fig. 1, however, cylinder 14 and wheel 16 are drivingly engaged by the clutch conventionally illustrated at 20 17, while, when said shaft is moved to the left, as viewed in Fig. 2, the wheel is unclutched from the cylinder in the usual manner. Thus cylinder 14 may be revolved by knob 15, whether or not the cylinder is drivingly engaged with wheel 16. When the wheel and cylinder are engaged, the cylinder is adapted to be revolved in a step by step manner by means of a pawl (not shown) which is given ratchet engagement with said 25 wheel by manipulation of a usual spacing lever (not shown). In order to prevent overrunning of the cylinder as revolved under influence of the aforementioned spacing lever, and to insure that the cylinder be not accidentally revolved from the position to which it is put, there is provided a brake roller 18 (Figs. 1 and 14) supported by a spring arm 19 which extends from frame 11. Roller 18 is of a size to be nicely taken between the 30 teeth 20 of wheel 16.

Supported from frame 11 in the usual manner (not shown, since the suspension means may be of any usual type and is not important to this invention) are the paper feed rollers 21, said rollers being supported on common shaft 22 and, with cylinder 14, determining the point of initial effective application of the paper to the typewriter. Rollers 21 are spaced apart along shaft 22, and since they are in line with each other and in axial parallelism with the cylinder, they act as an initial end stop for paper which may be introduced to them, lining up this edge of the paper (which is to be the top 35 edge of the finished sheet or envelope) in parallelism with the cylinder axis. As stops adapted to determine the initial position of the leading edge of the paper, the rolls enter into combination with the means for 40 moving the paper through a predetermined

extent of travel during a single actuation of the cylinder revolving or paper-advancing mechanism, to establish the predetermined point on the paper which is to line up with the type of the machine.

70 An inclined paper table 23 is supported from the frame 11 by any suitable means, for instance, through the medium of arms 24 pivotally mounted on frame rod 25. These arms have pivotal connection at 26 with angular lugs 27 on a slide bar 28, the rear face of table 23 being held in sliding engagement with the bar by the upturned edge portions 29 of said table (Fig. 3). At either side of upturned portions 29, the table is turned back 80 and upwardly at 30 and pressed closely to the table, proper, as in Fig. 4, to provide tracks having bearing edges 31 to receive the lower edge of bar 28.

85 Edges 31 and the opposing edges 32 of blocks 33, spaced above edges 31, prevent relative transverse movement of the table and slide bar. Blocks 33 are held between the table, proper, and portions 29 by bolts 34, and it will be evident that table 23 may be 90 shifted longitudinally to the right to any point between that shown in Fig. 1 and a position where side edge 35 of the right-hand portion 29 engages the inner face of the right hand arm 24^a. A clamping screw 36 extends through table 23 and one portion 29 whereby that portion may be drawn into clamping engagement with bar 28 to hold the table in adjusted position.

95 Extending from and between arms 24 is 100 a U-shaped spring brace 37 which engages the table-carried bracket 38 in a manner to hold the said table releasably in operative position, as shown in Fig. 14.

105 Leading from the lower edge of table 23 to feed rollers 21 is the usual guide plate 39, and extending between rollers 21 and rollers 21^a is the usual, arcuate guide 40, the table, rollers and guides thus being adapted to pass paper from the rear to the front of cylinder 110 14 in the usual manner.

115 The left-hand edge of table 23 is preferably turned over as at 41 (Fig. 5) to provide a side guide 42. The vertical extent of the side guide is such that paper is readily lined up therewith, and said guide is so positioned with respect to rollers 21 that when a paper is moved into side-edge engagement with guides 42 and in leading-edge engagement with rollers 21, it is assured that subsequent rotation of the cylinder will draw the paper squarely through the machine so the type lines will be parallel to the upper and lower edges of the paper.

120 The turned over side edge 42 may be cut out as at 43 in order to lighten the table and also to give access to the side of the paper between two guide points 42^a and 42^b so said paper may be drawn over into full engagement with said guide points, though, ordi- 130

narily, this operation is not necessary since a skilled operator will insert the paper with one move in such a manner that it properly engages said guide points as well as rollers 21.

It is helpful to provide means for taking or carrying gage marks on table 23, so the operator, by referring to the relative position of a gage marking and the following edge of the paper may note whether or not the paper feeding device is advancing the paper to a predetermined position. This is especially helpful when the device is being reset to a given stroke after a period of use at other than the given stroke. Considering the invention in its broader aspects, such gage markings may be permanently stamped or affixed to the forward face of table 23 as at 44, though a more convenient provision is the paper strip 45 threaded through the vertically spaced table-slits 46, this provision allowing a proper support for the strip 45 upon which gage marks 44^a may be marked with pencil or pen, unmarked portions of the paper being readily exposed, when a new gage setting is to be made, merely by slipping the paper through slits 46.

The improved cylinder revolving device is indicated generally at 47, and includes a supporting member 48 which is preferably adapted to be detachably secured to frame 11. However, it will be understood that bodily detachment of the device is not essential to the invention, considered in its broader aspects, and that therefore, the frame 11, itself, may be considered as the supporting member. This broad characterization of the supporting member is contemplated in the appended claims, except in those which definitely specify the supporting member as being an element bodily detachable from the carriage frame.

Where the supporting member is made separately from the carriage frame, the means for applying it to said frame depends almost wholly upon the character of the particular machine to which application is made. In other words, when the typewriter is of a given make, the attachment means may have certain characteristics which may have to be altered considerably before the supporting member may be applied effectively to typewriters of a different make. Therefore, while we have shown attachment means which are particularly effective for applying the device to a certain make of typewriter, this specific showing is not to be considered as in any way limitative on the invention as regards the connective elements between carriage frames and supporting members.

In the illustrated embodiment, supporting member 48 (Fig. 12) has an arcuate portion 49, a central hub portion 50, and a radially extending arm or bracket portion 51. Arm 51 and a second, angularly spaced arm 52, join the arcuate portion 49 and hub portion

50. The supporting member also has a radially extending arm 53 which has a transversely bent forked end 54 (Fig. 8) adapted to hook over bar 55 of carriage frame 11. Attachment between frame 11 and member 48 70 is completed by a transversely bent arm 56 which extends from member 48 (Fig. 1), and is terminally and detachably secured by screw 57 to the end of frame-rod 25.

Hub portion 50 supports a stationary stub 75 shaft or stud 58 which is concentric with arcuate portion 49, while cylinder shaft 13 extends, with bearing, through arm 51 in axial parallelism with stud 58. Beyond the outer face of arm 51, shaft 13 (Fig. 10) carries a pinion 59 which is in mesh with relatively large gear 60, the latter being carried for free axial rotation on stud 58. Gear 60, which may be termed a driving member, has a relatively large diameter hub portion 61, and a relatively small diameter hub extension 62, a collar 63 being held to the shaft by set screw 64 (Fig. 6) to hold the gear from moving longitudinally along the shaft.

We have here shown gear 60 serving the dual function of a drum adapted to be engaged frictionally by a driving or gripping shoe, and for imparting the movement of the driving shoe, with speed advantage, to pinion 59. In other words, the teeth of the gear are adapted to engage the pinion drivingly, and also to receive the bearing face of a driving shoe. While this is a feature of advantage, it will be readily understood that it lies within the scope of our invention to utilize the gear teeth only as a means for driving the pinion and to utilize a separate peripheral face operatively connected to the gear for receiving the driving shoe.

Driving or gripping shoe 65, having an 105 arcuate gripping face 66 which is substantially complementary to the peripheral face of gear 60, is held in vertical alignment with the gear by a shoe-supporting arm 67, the shoe preferably being detachably connected 110 to the transverse extension 68 of said arm by screw 69 (Fig. 7) in order that the shoe may be readily replaced when it becomes unduly worn. The shoe may be made of any suitable material, preferably being of softer material than is gear 60. For instance, when gear 60 is made of bronze, shoe 65 may be made of any softer alloy such as nickel-babbitt, and if the gear is made of steel, the shoe 115 may be made of annealed copper.

Shoe 65 and arm 67 are adapted to be moved longitudinally, or substantially radially with respect to shaft 58, to bring said shoe into and out of gripping or operative relation with the peripheral faces of the teeth of gear 60, and the shoe and arm are also adapted to be oscillated circumferentially through a gear-driving or work and idling stroke. This circumferential movement of the arm is accomplished through actuation of 125 130

a carrying member 70 on which said arm is mounted in a manner to have the described limited longitudinal or radial movement, while it is held against transverse displacement with respect to the carrier member by the means now to be described. Carrier member 70 includes a hub portion 71 which is mounted for rotation on gear hub 62 and held against endwise displacement with respect to the gear by hub shoulder 72 and collar 63. Extending radially from hub or sleeve 71 is arm 73, screw 74 securing a substantially rectangular frame portion 75 to the upper end of the arm, said frame defining a transversely extending slot 76 (Fig. 11). Shoe arm 67 is held between arm 73 and gear 60, said shoe arm and arm 73 being in sliding, facial engagement, though the upper end of the shoe arm is held between transverse shoulder 74 and a frame-carried stud 77 to prevent its transverse displacement with respect to the carrier member. The lower end of the shoe arm is held from such movement by means of its integral fork arms 78 (Fig. 10) which extend at opposite sides of gear hub 61.

Circumferential, oscillatory movement of the carrier member and radial and circumferential movement of the shoe arm and shoe is accomplished by actuation of operating lever 79, the shank 80 of said lever extending through slot 76 and terminating in transverse handle 81. The operating lever is mounted for oscillation with respect to carrier 70 by means of a stud 82 which has bearing in carrier arm 73 (Fig. 7), and a stud 83 projects from the inner face of shank 80 in eccentric relation with stud 82 and into a clearance aperture 84 provided in shoe arm 67. Pin or stud 83, which may be considered a cam, is so disposed that, with carrier 70 held relatively stationary, swinging movement of lever 79 to the right, as viewed in Fig. 6, moves the stud downwardly into bearing engagement with the lower defining wall of aperture 84 and thus moves arm 67 substantially radially inward in a manner to engage shoe 65 operatively or frictionally with gear 60. However, a spring 85 is applied to carrier 70 and lever 79 at 86 and 87, respectively, in a manner normally and yieldingly to hold lever 79 against this right-hand movement and in the position of Fig. 11, in which position arm 67 is held upwardly by pin 83 in a manner to provide clearance between shoe 65 and gear 60. In other words, spring 85 is adapted yieldingly to hold shoe 65 in inoperative position.

It will be seen that due to the ratio between gear 60 and pinion 59, comparative slight angular movement of said gear through actuation of lever 79, after the driving shoe has been engaged with said gear, imparts very considerable angular movement to the cylinder shaft and cylinder. The extent of angular movement of the carrier member and

shoe, or in other words, the effective stroke of the shoe, is determined by limiting stops, one of which, at least, preferably, though not necessarily, is adjustable whereby the stroke may be varied to suit various conditions. We have herein shown preferred forms of stops, but it will be readily understood it lies within the scope of our invention, considered in its broader aspects, to utilize other forms of stops or to combine one of the stops here shown with stops of a nature other than that here shown.

As a means for limiting the clockwise movement of the carrier member, as viewed in Figs. 6 and 9, we have here employed a stop wheel 88 fast on shaft 13, and a coacting lug 89 on carrier frame 75. Considered broadly, wheel 88 may be thought of merely as a shoulder carried by frame 11 in fixed effective position, it being evident that when carrier 70 is drawn down to the position of Fig. 9, lug 89 contacts with the peripheral face or shoulder of the wheel to prevent further clockwise rotation of the carrier member and its associated elements. As an additional feature, though this is not essential to the invention, we provide wheel 88 with peripheral teeth 90 facing in a direction opposite the teeth of ratchet 16 and of an equal number therewith. The effective edge 91 of lug 89 is of a shape to enter between the wheel teeth when carrier 70 is at the end of its stroke. The purpose of this lug and tooth engagement will be made apparent later.

The stop determining the other end of the stroke is designated generally at 92, and may be considered as a shoulder which is movable, preferably through an arcuate path, to vary the angular extent between it and stop 88, thereby to vary the angular extent or stroke of carrier 70. A preferred, though not a limiting, form of adjustable stop is shown in detail in Fig. 13. A yoke 93 straddles arcuate portion 49 of supporting member 48, a pinion 94 being confined between the yoke arms and being mounted on a shaft 95 journaled in said arms. The pinion is held in mesh with the teeth 96 provided on the peripheral face of arcuate portion 49, said arcuate portion being concentric with gear 60. The free arm extremities 93^a of yoke 93 extend below arcuate portion 49 and are adapted to be releasably clamped thereto by clamping screws 97, the operation of which will be readily understood. Shaft 95 carries an operating knob 98, rotation of said knob causing movement of yoke 93 along the arcuate portion of the supporting member when the clamping screws are loosened, said screws being taken up when a predetermined position of adjustment has been reached.

Yoke 93 has a transversely extending lug 99 presenting a stop shoulder 100 in the path of carrier member 70, the transverse extension 101 (Figs. 10 and 11) of carrier frame 130

75 being adapted to engage shoulder 100 to limit the counterclockwise movement of said carrier, as viewed in Figs. 6 and 9.

Secured to lug 99 is a U-shaped retention 5 spring or yieldable latch 102, this spring having a downwardly bent hook or shoulder portion 103 which is angularly spaced ahead of shoulder 100, this spacing being just sufficient to take extension 101 of the carrier member 10 ber frame.

Spring 102 is thus adapted normally to hold the carrier member yieldably in the position of Fig. 6, and the spring is of greater effective strength than is spring 85 so handle 15 lever 79 may be swung in a clockwise direction (Fig. 6) from full to dotted line position against the action of spring 85 without freeing the carrier member from the latching tendencies of spring 102.

20 Applied to carrier member 70 and collar 63 at 104 and 105, respectively, is a spiral spring 106, this spring resisting clockwise movement of the carrier member (as viewed in Fig. 6) and being of a strength to return

25 the carrier from the position of Fig. 9 to that of Fig. 6, when the operating lever is released from the hand, and to engage carrier extension 101 beneath hook 103 at the end of such counterclockwise movement.

30 Assuming now that the paper to be written upon (not shown) is entered between cylinder 14 and feed rolls 21 as previously described, the operator then grasps handle 81 and swings lever 79 in a clockwise direction, as viewed in Fig. 6. The first effective movement is to swing the operating lever with respect to the carrier member 70, said carrier member being initially held against swinging movement by spring 102. Consequently, cam 35

40 83 acts against shoe arm 67 in a manner to engage shoe 65 operatively with gear 60, that is, it is drawn into frictional contact with the peripheral faces of the gear teeth. As soon as radial or longitudinal movement 45 of the shoe arm is checked, continued clockwise movement of the operating lever moves the carrier from beneath spring 102 and the carrier with the shoe is thus rotated in a clockwise direction. Due to the frictional

50 engagement between the shoe and gear 60, said gear is rotated in the same direction and causes a consequent rotation of pinion 59 and cylinder 14 in the opposite or paper-feeding direction. Since the ratio of gear 55 60 and pinion 59 may be four to one, more or less (of course, this ratio may be varied within reasonable limits to meet various situations) comparatively slight angular movement of the lever is sufficient to rotate the cylinder enough to bring the leading edge of the paper clear beneath the cylinder and sufficiently beyond the effective platen surface thereof to present to the type a portion of said paper which is spaced considerably

60 65 from said leading edge. This cylinder move- 70

ment is equivalent in angular extent to that which could be accomplished by the usual line-spacing mechanism only after repeated ratcheting movements thereof, or by several turns of the cylinder knobs. 75

Ordinarily, of course, the operating lever is swung until lug 89 engages a stop wheel 88, but the following movements would also occur in the event the operator releases the lever before such engagement takes place. As soon as down-bearing pressure on the operating lever is relieved, spring 85 immediately comes into play to swing said lever in a counterclockwise direction (as viewed in Fig. 9) with relation to carrier 70. By virtue of this rotation, the eccentric cam 83 moves arm 67 radially outward and carries shoe 65 clear from or out of operative engagement with gear 60. Thereupon, spring 106 rotates the carrier back to the position of Fig. 6, extension 101 being snapped beneath spring hook 103 and into engagement with shoulder 100, the device then being in condition for subsequent operation. 80

85 It will be noted that except when the carrier member is held against circumferential movement the operating lever cannot be swung with respect to said member in a manner to engage the shoe with the gear. Consequently, the operator once having relieved the down-bearing pressure on handle 81 at the completion of the work stroke, cannot again engage the shoe with the gear at any point between its stroke limits, assuring full 90 work strokes. 100

95 It may be noted at this point, that the application of the device above described in no way interferes with the normal operation of the line spacing mechanism nor with the rotation of the cylinder by movement of knobs 105 15. This is for the reason that rotation of said cylinder by the usual means merely causes rotation of gear 60 through the medium of pinion 59, said gear revolving freely or idly upon shaft 58. 110

115 The coaction of lug 89 with stop wheel 88 brings about a condition which is particularly desirable. This is true whether or not the stop wheel be of the toothed type shown, in fact it is of particular merit when the wheel does not have the toothed characteristics to be described later. This condition arises from the fact that when the stop lug engages the stop wheel, the carrier member is held against further clockwise circumferential movement and consequently the down-bearing force applied to lever 79 acts through cam 83 to engage the gripping shoe more forcibly with gear 60. Consequently, the tendency of the cylinder to over-run, by virtue of its acquired momentum, is checked, this checking being advantageous both for the reason that it insures proper lining up of the paper with the type and for the reason that it prevents undue wear on the shoe or gear teeth which 120 125 130

might occur were relative slippage to exist while the shoe is partially pressed upon the gear.

We will now discuss the particular merits of providing stop wheel 88 with peripheral teeth, said teeth being equal in number and facing oppositely to those of ratchet 16. The teeth of wheels 16 and 88 are so lined up, that when lug 89 is entered fully between the teeth of wheel 88, roller 18 is fully entered between the teeth of ratchet wheel 16. Stop 92 is always so adjusted that such entry of the lug with the teeth of wheel 88 is assured, and consequently at the end of each stroke it is assured that roller 18 enters between the teeth of ratchet 16. Thus, lug 89 meets a cam tooth of wheel 88, which is revolving in a direction opposite to that of the rotation of the lug about shaft 58 and hence of the handle about said shaft, positively to limit the extent of the work stroke and to prevent over-run of the cylinder, and, due to the full entry of roller 18 between the teeth of ratchet 16, as soon as the shoe is relieved from gear 60, said roller is in proper braking engagement with the ratchet wheel. In other words, it is assured that at the end of the work stroke the roller is properly engaged with the ratchet rather than riding the teeth thereof in such a manner that slight jar of the typewriter might subsequently shift the cylinder to carry it out of predetermined position.

It will be understood the drawings and description are to be considered merely as illustrative of and not restrictive on the broader claims appended hereto, for various changes in design, structure and arrangement may be made without departing from the spirit and scope of said claims.

40 We claim:

1. In a device of the character described, a rotatable driving member, a carrier mounted for rotation with respect to said driving member, a driving shoe carried by the carrier and mounted thereon for movement into and out of operative engagement with the driving member and normally out of such operative engagement, an operating lever movably mounted on the carrier member and movable with respect to the shoe, and an operative connection between the lever and shoe whereby the shoe is moved into and out of such operative engagement by virtue of lever-motion.
- 55 2. In a device of the character described, a rotatable driving member, a carrier mounted for rotation with respect to said driving member, a driving shoe carried by the car-

rier and mounted thereon for movement into and out of operative engagement with the driving member, an operating lever movably mounted on the carrier member, an operative connection between the lever and shoe whereby the shoe is moved into and out of such operative engagement by virtue of lever movement, and means yieldingly holding said shoe out of such operative engagement.

3. In a device of the character described, a supporting member, a driving member rotatably mounted on the supporting member, a carrier mounted for selective rotation with and with respect to the driving member, a driving shoe mounted on the carrier for movement with respect thereto into and out of operative engagement with the driving member, and a spring catch movably mounted on the supporting member and adapted normally and yieldingly to hold the carrier from rotation with respect to the supporting member.

4. In a device of the character described, a supporting member, a cylinder mounted for rotation with respect to said member, a driving member rotatably mounted on the supporting member and drivingly connected to the cylinder, means for rotating the driving member, a stop member adapted to be rotated by the cylinder, and a stop member associated with said rotating means, said stop members being adapted to engage one another after said rotating means has been given predetermined actuation and thereby to check rotation of the cylinder.

5. In a device of the character described, a supporting member, a cylinder mounted for rotation with respect to said member, a driving member rotatably mounted on the supporting member, gears drivingly connecting the driving member and cylinder, means for rotating the driving member, said rotating means including an oscillatory member, the gears being arranged so swinging movement of said oscillatory member in one direction rotates the cylinder in the opposite direction, a toothed wheel adapted to be rotated by and in the same direction as the cylinder, and a stop on said oscillatory member adapted to engage the teeth of the wheel after said oscillatory member has been swung a predetermined distance in said one direction.

In witness that we claim the foregoing we have hereunto subscribed our names this 7th day of January, 1927.

GUY V. NEWTON.
ERNEST BLACKBURN.
